Primary Examiner — Mark Goodwin

(57) **CLAIM**

The ornamental design for a tractor switch, as shown and described.

DESCRIPTION

FIG. 1 is a perspective view of a tractor switch showing our new design.

FIG. 2 is a front view thereof.

FIG. 3 is a left side view thereof.

FIG. 4 is a right side view thereof.

FIG. 5 is a rear view thereof.

FIG. 6 is a top view thereof; and,

FIG. 7 is a bottom view thereof.

The broken line shown in FIG. 5 is included for the purpose of illustrating a portion of the tractor switch and forms no part of the claimed design.

The nature of this product is a tractor switch for controlling a tractor or other work vehicle, such as used in the agricultural, landscaping or construction industries.

1 Claim, 3 Drawing Sheets(56)
